UNITED STATES PATENT OFFICE.

RENE P. PIPEROUX, OF WESTWOOD, NEW JERSEY, ASSIGNOR TO CELLULOID CORPORATION, A CORPORATION OF NEW JERSEY.

DESIGN FOR A TOILET RECEPTACLE OR SIMILAR ARTICLE.

Application filed February 26, 1929. Serial No. 30,219. Term of patent 3½ years.

To all whom it may concern:

Be it known that I, RENE P. PIPEROUX, a citizen of the United States, residing at Westwood, in the county of Bergen and State of New Jersey, have invented a new, original, and ornamental Design for a Toilet Receptacle or Similar Article (Case 3), of which the following is a specification, reference being had to the accompanying drawing, forming part thereof.

tacle or similar article, showing my new design.

Figure 2 is an elevational view.

I claim:

The ornamental design for a toilet receptacle or similar article, as shown and described.

RENE P. PIPEROUX.
